UNITED STATES PATENT OFFICE.

JAMES F. McELROY, OF ALBANY, NEW YORK; SUSIE HALE McELROY, EXECUTRIX OF SAID JAMES F. McELROY, DECEASED, ASSIGNOR TO CONSOLIDATED CAR-HEATING COMPANY, A CORPORATION OF WEST VIRGINIA.

VALVE.

1,157,285.

Specification of Letters Patent. Patented Oct. 19, 1915.

Application filed February 15, 1909. Serial No. 477,868.

To all whom it may concern:

Be it known that I, JAMES F. McELROY, a citizen of the United States, residing at Albany, in the county of Albany and State 5 of New York, have invented certain new and useful Improvements in Valves.

My present invention relates to valves for controlling the admission and exhaust of fluids to and from fluid motors and more 10 particularly to controlling the operation of a fluid motor door operating mechanism, such as is described in my application for Letters Patent filed February 15, 1909, Serial No. 477,867, and has for its object the provision 15 of a valve whereby the admission and exhaust of compressed fluid to and from each end of the motor cylinder and the movement of the motor piston can be controlled with ease and certainty.

20 In the accompanying drawing:—Figures 1, 2 and 3 show horizontal sections of my improved valve in the various positions assumed during operation. Fig. 4 shows an arrangement of controlling levers of handles, adapted to operate my improved valve. 25 Fig. 5 shows a plan view of two of my improved valves connected to such operating mechanism.

Referring to the drawings, the valve 30 comprises a housing 1 in which is rotatably mounted a plug 2, held in position in suitable manner. The casing is provided with the supply passage 8, the exhaust passage 9, while 10 and 11 are working passages which 35 are connected to the opposite ends of the motor cylinder. The ports in plug 2 are preferably arranged as shown in the drawing, consisting of two cross ports 12 and 13 and two diagonal ports 14 and 15, communicating with cross port 13 and with each other.

The operation of my improved valve is as follows: In the position shown in Fig. 1, the compressed fluid is being supplied through 45 passage 8, port 12 and passage 10, to one end of the motor cylinder, while it is being exhausted from the other end of the motor cylinder through passage 11, port 15, port 14 and passage 9. When the valve is turned 50 to the position shown in Fig. 2, compressed fluid is being supplied to the other end of the motor cylinder from that to which it was supplied when the valve was in the position shown in Fig. 1, through passage 8, port 12

and passage 11, and it is being exhausted 55 from the opposite end of the motor cylinder through passage 10, port 14, port 15 and passage 9.

Fig. 3 shows an intermediate position between those shown at Figs. 1 and 2, in which 60 position the supply and exhaust ports are both closed, and the two working passages leading to the ends of the motor cylinder are connected to each other through passage 11, port 13, and passage 10. This position 65 is useful for stopping the motor at any point in its stroke by equalizing the pressure in the two ends of the motor cylinder, and as this position occurs during the change of 70 position of the valve from the position shown in Fig. 1 to that shown in Fig. 2, part of the fluid contained in one end of the motor cylinder will pass into the opposite end of the motor cylinder before that end is connected to the source of supply, thereby 75 saving a considerable quantity of compressed fluid in the operation of the motor.

When the valve is in the position shown in Fig. 3, the door or other object operated by the motor may be operated by hand, since 80 the fluid in the motor cylinder may be forced from one end of the motor cylinder to the other. When the valve is moved to the cut-off position intermediate between the operating positions and the short circuiting positions just described, the door will be checked pneumatically and locked against movement in either direction. This allows 85 the door to be first checked and then, by a further movement of the valve, short circuited, so as to be free for manual operation. 90

Fig. 4 shows mechanism for operating two sets of valves from the same position. It consists of a rod or pipe 17, surrounded by a pipe 18. Rod 17 has at one end of it a 95 handle 19, and pipe 18 has attached to it a handle 20. At the opposite ends of rod 17 and pipe 18 are attached levers 21 and 22, which are connected to the respective valves by means of links, as shown in Fig. 5. The 100 two operating handles 19 and 20 form respectively the top and bottom portions of a loop which may be conveniently grasped by the hand to work both handles together, while either handle may with equal convenience be worked separately. 105

In view of the numerous modifications which may be made, I do not desire to con-

fine myself to the precise structure illustrated and described.

No claim is made in this application, for details of the valve, nor for a door operating method, as the same form the subject-matter of an application filed November 15, 1913, Serial Number 801,164.

What I claim as new and desire to secure by Letters Patent of the United States, is:

- 10 1. The combination with two separate motor-controlling valves, of adjacent operating handles therefor forming the respective halves of a common loop handle.
- 15 2. The combination with two separate motor-controlling valves, of parallel operat-

ing shafts therefor, and handles on the respective shafts, forming respectively the two halves of a common loop handle.

3. The combination with two separate motor-controlling valves, of concentric operating shafts therefor, and operating handles on said shafts, forming the respective halves of a common loop handle.

In witness whereof, I have hereunto signed my name in the presence of two witnesses, this 11th day of February 1909.

JAMES F. McELROY.
